UNITED STATES PATENT OFFICE.

JOHN H. BRUMBAUGH, OF WILMETTE, ILLINOIS, ASSIGNOR TO AUTOMATIC SPRINKLER COMPANY OF AMERICA, OF NEW YORK, N. Y., A CORPORATION OF NEW YORK.

METER ALARM VALVE.

1,414,723.

Specification of Letters Patent.

Patented May 2, 1922.

Application filed November 17, 1917. Serial No. 202,463.

To all whom it may concern:

Be it known that I, JOHN H. BRUMBAUGH, a citizen of the United States, and resident of the village of Wilmette, county 5 of Cook, and State of Illinois, have made a certain new and useful Invention Relating to Meter Alarm Valves, of which the following is a specification, taken in connection with the accompanying drawing, which 10 forms part of the same.

This invention relates especially to meter alarm valves for use in connection with automatic sprinkler systems or other fire protection systems, the alarm valve having 15 in connection therewith an electric or other alarm signal actuated when the valve opens in the event of fire. A meter device is also arranged so that when the valve opens the water supply for moderate extinguishing 20 or other purposes will flow through the meter to thereby measure the water flow, while for unusually large requirements the valve may open wider so as to allow the water to flow at least in part past or around the 25 meter and without undesirably decreasing the effective head of the extinguishing liquid.

The accompanying drawing shows in a somewhat diagrammatic way an illustrative embodiment of this invention in vertical 30 section, parts being removed for greater clearness.

The valve casing 1 of any suitable form and material may be bolted or otherwise connected to the distributing system 2 so 35 that in the event of fire extinguishing liquid is supplied to the automatic sprinkler heads or other distributing devices arranged at various parts of the building. The valve casing may also be similarly secured to a 40 supply pipe 3 connected to the municipal or other water supply so as to furnish extinguishing fluid to the distributing system under fire emergency conditions. The alarm valve 33 which may be of any desired type 45 or construction may comprise the valve 33 cooperating with the valve seat 34 and may as indicated be pivotally mounted as by having the valve body 9 secured to valve arm 24 and stem 23 by the nut 8 on the stud 7. In 50 this way the valve is guided during its opening movement and the resistance which it offers may be regulated in any suitable way as by securing the desired weight 5 to the valve by screwing it on the depending end 55 of the stud 7. If desired also an auxiliary washer 6 may thus be secured to the lower part 10 of the valve body so as to properly close the upper end of the passage adjacent the valve seat 34 and regulate the flow of liquid during the opening movement of the 60 valve as is desirable in some instances.

In order to direct the flow through the meter devices during ordinary extinguishing action of the apparatus or other withdrawal of water therefrom a suitable valve 65 collar, such as 35, may be arranged adjacent the valve seat and preferably though not necessarily formed integral therewith, of a single bronze or other non-corrodible casting, for instance, so as to provide the valve 70 throat 12 of such shape as to accommodate the valve during its rising movement. A substantially tight joint may be made between the valve and throat by the use of a suitable throat washer 11 screwed or otherwise 75 secured to the alarm valve below the holding plate 38. In this way the first opening movement of the valve so as to assume a partially open position does not give direct connection between the supply 80 pipe and the valve chamber 4 communicating with the distributing system above, but merely opens the by-pass or meter passage 85 13 communicating with the distributing system through a meter device of any suitable character so as to measure the amount of 90 water or other extinguishing liquid which flows past the valve. This meter device may, for example, comprise the turbine meter wheel 14 having the spiral passages 32 in 95 its periphery and revolvably mounted on the meter shaft 15 so as to revolve therewith when water is flowing through the meter passage and communicating meter chamber 37. This movement may be indicated or 100 recorded by any suitable mechanism such as the reduction gears 16 transmitting a slower rotary movement to the indicator shaft 17 so as to actuate the indicator wheels or members 18 in the indicator casing 19 105 which may be provided with an open side or with a transparent window, if desired. For convenience of construction and assembly, the meter device may be mounted in a sectional or other meter casing 20, 21, to 110 which the indicator casing may also be secured, if desired, the various parts of the meter, such as the support 22 for the reduction gears being screwed or otherwise secured to this casing so that the whole may

be bolted or otherwise attached to the valve casing and make tight joint therewith.

In this way the amount of water flowing past the valve under any ordinary fire emergency operation of the sprinkler apparatus, etc., is indicated or metered with the desired accuracy. At the same time an extreme demand from the sprinkler system would cause the further lifting of the alarm 10 valve so that it would rise clear of the valve throat and thus allow water to flow directly past the valve and into the distributing system without passing around through the meter device or being retarded in this way. 15 The alarm valve may have connected therewith any desired alarm mechanism, such for example, as the alarm closer arm 25 which may be secured to the valve stem 23 outside of the casing and have connected therewith the alarm switch 26 cooperating with the alarm sectors 27, 28. The opening of the alarm valve through the connected closer arm moves this switch into electrical contact with the alarm sectors so as to close the 20 alarm circuit 29 in which they are included, together with the battery or other source of potential 30 and the electric bell or other alarm signal 31 which may be located at any desired or convenient point to give the usual alarm signal when the valve opens. Additional testing or indicating devices may, of course, be used in connection with the valve, such, for instance, as the pressure or indicator connection 39 with which a 25 pressure gauge or the like may be connected.

This invention has been described in connection with a number of illustrative forms, proportions, parts, materials, arrangements and devices, to the details of which disclosure the invention is not of course to be limited, since what is claimed as new and what is desired to be secured by Letters Patent is set forth in the appended claims:

1. In meter alarm valves for automatic 45 sprinkler systems, a valve casing adapted to be connected to a sprinkler distributing system and to a municipal water supply system, an alarm valve mounted in said casing, a connected valve arm and valve stem to guide said alarm valve in its opening movement, an electric alarm device comprising an alarm signal and an alarm switch connected to said valve stem to actuate said alarm signal when said alarm valve opens, a valve seat with which said alarm valve cooperates and a throttling valve collar formed integral with said valve seat to form a valve throat through which said alarm valve moves during its opening movement, a throat washer mounted on said alarm valve to make substantially 50 tight joint between said alarm valve and throat during the first opening movement of said alarm valve, a meter passage communicating with said throat and adjacent said valve seat, a turbine meter device to receive the fluid flowing from said meter passage into said distributing system when said alarm valve first opens, said alarm valve having emergency opening movement out of said valve throat to allow direct flow of 55 liquid through said throat and into said distributing system without passing through said meter device.

60 2. In meter alarm valves for automatic sprinkler systems, a valve casing adapted to

meter device mounted in a sectional meter casing secured to said valve casing to receive the fluid flowing from said meter passage into said distributing system when said alarm valve first opens, an indicator mounted outside of said valve casing and connected to said meter device, said alarm valve having emergency opening movement out of said valve throat to allow direct flow of liquid through said throat and into said distributing system without passing through 75 said meter device.

2. In meter alarm valves for automatic 80 sprinkler systems, a valve casing adapted to be connected to a sprinkler distributing system and to a municipal water supply system, an alarm valve mounted in said casing, an electric alarm device comprising an alarm signal and an alarm switch connected to said valve to actuate said alarm signal 85 when said alarm valve opens, a valve seat with which said alarm valve cooperates and a throttling valve collar formed integral with said valve seat to form a valve throat through which said alarm valve moves during 90 its opening movement, a meter passage communicating with said throat adjacent said valve seat, a meter device mounted in a meter casing secured to said valve casing to receive the fluid flowing from said meter 95 passage into said distributing system when said alarm valve first opens, said alarm valve having emergency opening movement out of said valve throat to allow direct flow of liquid through said throat and into said distributing system without passing through 100 said meter device.

3. In meter alarm valves for automatic 105 sprinkler systems, a valve casing adapted to be connected to a sprinkler distributing system and to a municipal water supply system, an alarm valve mounted in said casing, an electric alarm device connected to said valve to be actuated when said alarm valve opens, a valve seat with which said alarm valve cooperates, a valve collar with said valve seat to form a valve throat through which said alarm valve moves during its opening movement, a throat washer mounted on said alarm valve to make substantially 110 tight joint between said alarm valve and throat during the first opening movement of said alarm valve, a meter passage communicating with said throat and adjacent said valve seat, a turbine meter device to receive the fluid flowing from said meter passage 115 into said distributing system when said alarm valve first opens, said alarm valve having emergency opening movement out of said valve throat to allow direct flow of 120 liquid through said throat and into said distributing system without passing through said meter device.

4. In meter alarm valves for automatic 125 sprinkler systems, a valve casing adapted to

- be connected to a sprinkler distributing system and to a municipal water supply system, an alarm valve mounted in said casing, an alarm device connected to said valve to be actuated when said alarm valve opens, a valve seat with which said alarm valve cooperates, a valve collar with said valve seat to form a valve throat through which said alarm valve moves during its opening movement, a meter passage communicating with said throat adjacent said valve seat and a meter device to receive the fluid flowing from said meter passage into said distributing system when said alarm valve first opens, said alarm valve having emergency opening movement out of said valve throat to allow direct flow of liquid through said throat and into said distributing system without passing through said meter device.
5. In meter alarm valves for fire protection systems, a valve casing adapted to be connected to a distributing system and to a municipal water supply system, an alarm valve mounted in said casing, an alarm device connected to said valve to be actuated when said alarm valve opens, a valve seat with which said alarm valve cooperates, a meter passage normally substantially closed by said valve and communicating with said valve seat and with the portion of said valve casing adapted to be connected to said distributing system, and a meter device to receive the fluid flowing from said meter passage into said distributing system when said alarm valve first opens.
6. In meter alarm valves for automatic fire protection systems, a valve casing adapted to be connected to a distributing system and to a water supply system, a valve seat in said casing, a meter passage adjacent said valve seat and communicating with such distributing system connection, a meter device mounted to receive the fluid flowing from said meter passage into said distributing system, an alarm and an alarm valve actuating said alarm and cooperating with said valve seat to direct fluid into said meter passage during part of the opening movement of said valve and to allow the direct passage of part at least of the fluid into said distributing system without entering said meter passage when said valve opens further.
7. In meter devices for fire protection sys-
- tems, a valve casing adapted to be connected to a distributing system and to a water supply, a valve seat in said casing, a meter passage connected to said valve seat and adapted to be connected to said distributing system and a connected meter device to receive the fluid flowing through said passage into said distributing system, a valve cooperating with said valve seat to direct fluid into said meter passage during the first opening movement of said valve and to allow the direct passage of part at least of the fluid into said distributing system without entering said meter device when said valve opens further.
8. In meter devices for automatic fire protection systems, a casing adapted to be connected to a distributing system and to a water supply, a meter device and means comprising a controlling device to direct fluid into said meter device during the first movement of said controlling device under fire emergency conditions and to allow the direct passage of fluid into said distributing system without entering said meter device when said controlling means opens further.
9. In meter alarm valves for automatic sprinkler systems, a valve casing adapted to be connected to a sprinkler distributing system and to a water supply, a valve seat in said casing, a meter passage adjacent said valve seat and adapted to be connected with said distributing system, a meter device mounted to receive the fluid flowing from said meter passage into said distributing system, an alarm and an alarm valve actuating said alarm and cooperating with said valve seat to direct fluid into said meter passage during part of the opening movement of said valve.
10. In meter devices for automatic sprinkler systems, a casing adapted to be connected to a sprinkler distributing system and to a water supply, a meter device and a controlling device to direct through said meter device fluid passing from said water supply to said distributing system when said controlling device moves under fire emergency conditions.
